UNITED STATES PATENT OFFICE.

PHILIP G. BECKLEY, OF NEWARK, NEW JERSEY.

LAMP-WICK TRIMMER.

SPECIFICATION forming part of Letters Patent No. 271,022, dated January 23, 1883.

Application filed June 30, 1882. (No model.)

To all whom it may concern:

Be it known that I, PHILIP G. BECKLEY, of Newark, in the county of Essex and State of New Jersey, have invented a new and useful 5 Improvement in Lamp-Wick Trimmers, of which the following is a specification.

My invention relates to an improvement in lamp-wick trimmers, and is designed as an improvement on my former patent, No. 249,820, 10 of November 22, 1881; and it consists mainly in a peculiarly-constructed spring to operate on the lever, and also on the sliding cutting-plate, substantially as hereinafter set forth.

Figure 1 is a plan before cutting. Fig. 2 is 15 the same, showing the position after cutting a wick. Fig. 3 is a side elevation, showing the position before cutting.

In my construction the frame A is made with the guide and rest B to fit in the slot in the 20 top of the cone of a lamp-burner, and on the same end of the frame, on the upper side, is secured a fixed cutting-plate, C. These parts were the same in my former patent; but in this improvement back of the cutter C, in the top 25 of the frame, is a recess, D, into which is laid a sliding cutter-plate, E, fitted to cut the lamp-wick by being made to slide onto the end of the plate C. The lever F is hung to the frame, and has an end made to pass up through 30 a hole in the plate E. Through the end G of the lever, above the plate E, is put a pin, H, extending across the plate E, and on this pin is put a coiled-wire spring, I, in one piece of wire, made with duplicate parts, with an end, 35 K, made to hook upon each side of the rear end of the plate E, and a portion, L, in front

of the pin, made to press on each side of the top of the plate E. The spring is so made that the parts K and L have a tendency to come together below the pin, and on that account 40 the ends K, being caught over the rear end of the plate E and the front portion, L, bearing on the said plate, have a tendency to press the end G of the lever up, and this carries this end of the lever and the plate back after 45 the lever has been used to push the plate forward in the act of cutting a wick. The spring, from the peculiar construction, having the portion L bearing on the plate E, presses it down closely 50 on the frame and on the plate C, as it moves on it in cutting, and the pressure increases as the cutter E passes onto the cutter C, the portion L being carried farther from the pin, and this is just what is needed, the pressure on the sliding cutter being stronger at the point of 55 cutting the wick. The spring accomplishes the twofold work of reacting the lever and of pressing down the sliding cutter.

I claim—

1. In a wick-trimmer, the combination, with 60 the plate E and lever F, of the double-acting spring I, substantially as and for the purposes specified.

2. In a lamp-wick trimmer, the frame A, carrying the plates C and E, the lever having the 65 end G made to pass through the plate E, the pin H, and spring I, all substantially as and for the purpose set forth.

PHILIP G. BECKLEY.
